UNITED STATES PATENT OFFICE

RICHARD DEETJEN, OF BERLIN-WILMERSDORF, GERMANY, ASSIGNOR TO SIEMENS-SCHUCKERTWERKE AKTIENGESELLSCHAFT, OF BERLIN-SIEMENSSTADT, GERMANY, A CORPORATION OF GERMANY

MARINE VESSEL

Application filed January 5, 1929, Serial No. 330,568, and in Germany January 11, 1928.

My invention relates to improvements in marine vessels of all kinds, in which an electric motor is employed for any purpose and exposed to the risk of injury by sea-water.

5 This is, for instance, the case with electric motors by means of which a propeller is driven. To protect such a motor against the water it is usually housed in a chamber constructed of watertight walls. A watertight 10 wall is particularly necessary at the side of the driving motor facing the propeller. It is, however, necessary to provide this wall with a bore for passing through the driving shaft and a special stuffing-box is then necessary at this place.

According to my invention one bearing shield of the motor is adapted to serve directly as watertight wall. In this way a special partition wall with a packed opening for the passage of the motor shaft becomes superfluous, so that the space within the boat can be better utilized.

In the drawing affixed hereto and forming part of my specification is illustrated an embodiment of my invention, by way of example.

Referring to the drawing showing a sectional plan, 1 is the driving motor of a boat with the driving shaft 2. The bearing or end 30 shield 3 of the motor is designed as watertight partition or bulkhead and separates the compartment 4 at the rear end of the boat from the hold of the vessel. Between the motor compartment and the storage battery 35 compartment 5 may be provided a second bulkhead 6. The bearing shield or partition 3 may be provided with strengthening ribs to enable it to withstand high pressures.

My invention may also be applied to steering motors and other types of marine motors. It may equally well be used on torpedoes and submarines.

Various modifications and changes may be made without departing from the spirit and 45 the scope of the invention, and I desire, therefore, that only such limitations shall be placed thereon as are imposed by the prior art.

I claim as my invention:

1. In a marine vessel containing an electric motor for driving the propeller, a shield

on the propeller side of the motor having a watertight bearing and forming part of the motor casing, said shield extending beyond the circumference of said casing and adapted to serve as a watertight bulkhead for the vessel compartment in which the motor is located. 55

2. In a marine vessel containing an electric motor for driving the propeller, a shield on the propeller side of the motor having a watertight bearing and forming part of the motor casing, said shield extending beyond the circumference of said casing substantially to the vessel walls to serve as a watertight bulkhead for the vessel compartment in which the motor is located and a ledge on the inner walls of the vessel upon which said shield is mounted. 60 65

In testimony whereof I affix my signature.
